UNITED STATES PATENT OFFICE.

WILLIAM H. McGEE, OF AUSTIN, TEXAS.

CHARCOAL-BURNING APPARATUS.

1,387,060.

Specification of Letters Patent. Patented Aug. 9, 1921.

Application filed August 13, 1920. Serial No. 403,228.

To all whom it may concern:

Be it known that I, WILLIAM H. McGEE, a citizen of the United States of America, and resident of Austin, in the county of Hayes and State of Texas, have invented certain new and useful Improvements in Charcoal-Burning Apparatus, of which the following is a specification.

This invention relates to charcoal burning and particularly to burning devices known as charcoal pits, the said invention having for its object the provision of novel means whereby a superior product results while at the same time, the quantity produced from a given amount of raw material is greatly increased as compared with the products resulting from known methods and apparatus.

The invention has for its object the provision of a pit or furnace having refractory walls of strong and durable structure which will withstand the impact of the raw material when it is delivered to the pit without being seriously affected thereby; and the said invention has for its further object, the provision of means for permitting the convenient charging and discharging of the said pit.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a plan view of a charcoal pit and a roadway leading thereto;

Fig. 2 illustrates a view in elevation of the pit and the parts associated with it and the roadbed in section;

Fig. 3 illustrates a sectional view on the line 3—3 of Fig. 1, and

Fig. 4 illustrates a sectional view on the line 4—4 of Fig. 1.

While proportions do not enter into the limitations with respect to the construction of the invention, it has been found in practice that the best results are attained by having a pit which is not more than eight feet in depth and ten feet square with the upper surface of the wall about 2½ feet above the

ground. Preferably the walls of the pit are formed of concrete, rock, or brick.

In these drawings 5 denotes the pit, 6 the walls of the furnace or container which preferably are in spaced relation to the walls of the pit to permit the escape of the products of combustion emanated from the smoldering material within the furnace, and the rear and side walls of the said pit are provided with vents or openings 7 each of which is controlled by a damper 8 slideable in vertically disposed ways 9 formed in the walls of the furnace, the said dampers being operated by the damper rods 10 projecting at the top of the furnace so that they may be manipulated by an operator and adjusted to increase or diminish the venting area of the openings. The top or upper edges of the walls are recessed to form shoulders 11 constituting seats on which the doors 12 may rest, when in their lowermost positions. One of the doors 12 may also have an aperture 14 controlled by a small door 15 which is hinged as shown in Fig. 1 so that there may be an opening formed in the roof of the pit through which the contents of the pit may be fired. The front of the pit has a large door 16 hinged in the frame 17, and the said large door has a slot or opening 18 controlled by a flap door 19 for purposes of observation or for creating a draft.

The roof doors are preferably in two sections which overlap to produce a relatively tight joint and by their use, a draft is so controlled as to sufficiently smother the fire and cause the burning material to char instead of to burn freely.

By the use of a pit of the character indicated, the material being treated need not be covered with earth, straw or bark to prevent free burning as is now commonly done, so that much labor and material is saved, while the product is entirely free of foreign substance and is of a superior quality compared with that made in the ordinary way.

The earth in front of the pit is excavated to a depth equal to the height of the pit so as to form a roadway or stand for a vehicle delivering the wood to the pit as shown at 20 and the said roadway is inclined as at 21 and 22 in opposite directions so that a vehicle may approach and leave the pit without turning. The relation of the stand 20 to the pit is such that the vehicle or the body

thereof will be approximately at the top of the pit for convenient charging of the pit directly from the vehicle.

I claim:

- 5 1. In a charcoal burning apparatus, a pit, a furnace wall therein spaced from the wall of the pit, the said walls having openings through their sides and vertically disposed channels merging with the openings, dampers in the said vertically disposed channels adapted to enter the openings, damper rods connected to the dampers and slidable in the channels, doors adapted to close the top of the said furnace, and a door in the front of the said furnace.
- 10 2. In a charcoal burning apparatus, a pit,
- 15

a furnace wall therein spaced from the wall of the pit, the said walls having openings through their sides and vertically disposed channels merging with the openings, dampers in the said vertically disposed channels adapted to enter the openings, damper rods connected to the dampers and slidable in the channels, doors hingedly connected to the walls of the furnace and adapted to close the top of the said furnace, a door in the front of the said furnace, said door having an opening therein, and a flap door controlling the said opening.

WILLIAM H. McGEE.
